UNITED STATES PATENT OFFICE.

RALPH E. H. POMEROY, OF CANTON, OHIO.

PULVERIZING MILL.

Application filed July 10, 1922. Serial No. 573,905.

To all whom it may concern:

Be it known that I, RALPH E. H. POMEROY, residing at Canton, in the county of Stark and State of Ohio, a citizen of the United States, have invented or discovered certain new and useful Improvements in Pulverizing Mills, of which improvements the following is a specification.

In prior applications, to-wit: Serial Numbers 393,147, filed June 30, 1920; 474,079, filed June 1, 1921; 516,380 filed November 19, 1921; 522,360, filed December 14, 1921; and 539,417, filed February 27, 1922, are described and claimed improvements in the method of and apparatus for causing the permeation of currents of air through a charge or mass consisting of pieces of frangible material and objects formed of more durable material such as metal balls for the purpose of removing reduced particles from the zone of reduction. The means described and shown in said applications for directing the currents or streams of air into the charge or mass consist of a shell having perforated perimeter revoluble in a closed casing having an opening therethrough for the admission of air which passes into and through the charge in the shell, as perforations in the shell are brought into line with said opening. As in such a construction the formation of and maintenance of air-tight joints is difficult, the employment of air under pressure above atmospheric pressure results in the escape of pulverized material through such joints, and hence in the operation of the construction of apparatus shown and described in said application, the flow of currents of air into and from the reducing chamber is preferably induced by maintaining within such chamber and at the discharge outlet a pressure below atmospheric pressure. This is effected by connecting the outlet from the chamber to an exhaust fan or pump; and hence the pulverized material will pass through the pump or fan, which is in many cases undesirable.

The invention described herein relates to a construction of pulverizing mill permitting of the introduction at the inner periphery of the revoluble shell, of streams or jets of a fluid, as for example, air, at a pressure above atmospheric pressure, the circulation of the fluid within the shell and its escape therefrom, without a liability of the escape of fine material except through an outlet provided for that purpose. The

invention is hereinafter more fully described and claimed.

In the accompanying drawings forming a part of this specification, Fig. 1 is a sectional elevation of a pulverizing mill embodying improvements claimed herein, the plane of section being coincident with the axis of the mill; Fig. 2 is an elevation of a portion of the discharge screen or plate; Fig. 3 is a side elevation of the annular liners as viewed from the exterior; Fig. 4 is a lateral cross-section of the same; Fig. 5 is a longitudinal cross-section of the same showing the interior; Fig. 6 is a longitudinal cross-section showing modification of the form shown in Fig. 1; Fig. 7 is a portion and an end elevation of the end plate as shown in Fig. 6; Fig. 8 is a sectional elevation of a modified form of that shown in Fig. 1 showing the application of distributor head 15^e to any open end type of ball mill or pulverizer.

In the practice of the invention the drum in which reduction is effected consists of a cylindrical casing 1 having one end closed by a head 2 which is protected against abrasion by end liners 2^a, and having a hollow trunnion 3 through which material to be reduced is fed into the drum. Provision should be made for preventing the escape of fluid from the drum through the trunnion through which fuel is fed to the drum. While other means may be employed to prevent the escape of fluid, the construction shown has been found effective and consists of a positively driven feeder screw 4, arranged in the hollow trunnion to which material is supplied from a hopper in such quantity as to maintain the trunnion fully charged. At its opposite end the casing 1 which is preferably made of sheet metal, has secured thereto a ring or tire 5 adapted to ride on rollers 6 during the rotation of the drum by the power driven pinion 7 engaging the annular toothed member 8 secured to the head 2 of the drum. The casing serves as a retaining member for annular liners 9 so constructed as to form in connection with the casing a plurality of passages 10. The annular liners are retained in such relation to each other by intermeshing keys 10^a that continuous passages are formed from end to end of the drum. These passages are closed at one end by the head 2. The annular liners are held within the drum by a slotted head or grating 11 secured to the casing 1.

and having openings 12 adjacent to the periphery of the head and adapted, when the head is in position, to register with the passages 10 in the liners.

- 5 As it is desired that the fluid should escape from the passages 10 into the interior of the drum in directions approximately at right angles to the radii of the drum, the interior walls of the liners have approximately radial portions 13 (see Figs. 3 and 4) through which are formed perforations 14 so that the fluid will flow around the interior of the drum at an angle to the radii of the drum.

- 10 15 The fluid enters a stationary distributor-head A, through an opening controlled by valve 28 and flows outwardly into an annular chamber 16 formed by an outer hood 17 and an inner hood 21 having their inner ends secured respectively to the casing and the slotted head or grating 11 as shown in Fig. 1. From this annular chamber the air flows through ports 12 along passages 10 in the liners and through perforations 14 into the drum. Adjacent to its inner periphery the outer end of the hood 17 is provided with an annular surface 18 with which the inner end of the distributor head A forms an hermetic joint and to this end a packing 25 ring 19 is arranged at the inner end of the distributor head A, said ring being pressed against the surface 18 by springs 20.

- In the construction shown in Fig. 1 the inner portion of the head 11 is perforated as 35 at 11^a and the conical hood 21 is attached thereto, the line of attachment being intermediate the ports 12 and the slots 11^a. This hood extends from the head or grating 11 to the inner end of the outlet passage 25 in 40 the distributor head A and forms a chamber 23 into which the fluid carrying the fine particles enters after passing through the slotted head or grating.

- In order to prevent pulverized material 45 from accumulating in the circumferential portion of the inner chamber 23, lifting ribs or vanes 22 may be so attached to the inner surfaces of the hood 21 that as the drum revolves, pulverized material will be carried up and dropped at such points that it 50 will enter the stream of fluid passing through the chambers 23.

- As is well known in the art, the rate of flow of fluid through the drum and the charge therein should be regulated in accordance with the grade or degree of fineness of the material to be removed. The rate of flow being approximately inversely proportional to the fineness of the material 55 to be removed.

- It will sometimes occur, when the rate of flow is regulated to remove a particle of the desired fineness from the drum, that such rate will not be sufficient to carry the 60 pulverized material to the desired point out-

side the drum nor sufficient when fuel is being pulverized to effect complete combustion of the fuel. And further, it is not practically possible to so regulate the rate of flow of fluid as to remove from the drum 70 only material of specific fineness. Some coarser material will always be present in the material discharged from the pulverizer. If the presence of this small amount of coarser material is found to be detrimental in the finished product, the fluid carrying the material from the drum is passed through a separator or classifier 15^a immediately after leaving the pulverizer 75 which device serves to separate or classify the larger particles of material from the fine, and from the fluid which passes onward with the fine particles. The coarser particles when so removed may be returned to the pulverizer for subsequent further reduction in size until sufficiently small to pass through the separator with the air or fluid as material of suitable fineness. As it is not practicable to pass fluid 80 at a sufficient rate through the drum to effect separation or classification nor to carry the material forward from the drum nor to effect complete combustion, additional fluid for either of or all of these conditions is admitted to the chamber 23 85 through ports 24 in the hood 21, permitting fluid under pressure to flow from the chamber 16 into the chamber 23. These ports are preferably located adjacent to the head or grating 11, and when so located the inflowing stream of air will supplement the action of the vanes 22 in preventing an accumulation of fine material in the outer portion of the chamber 23.

In case the fluid flowing through the 90 drum and entering through the ports 24 is not sufficient to effect classification, to carry forward the material, or effect desired combustion, additional fluid may be admitted to the stream of fluid and material passing from the discharge passage 25, through the passage 27 in the distributing head and controlled by valve 29.

It is characteristic of the improvement described and claimed herein that the fluid 105 employed for the removal of fine material from the pulverizer enters the drum in a direction substantially parallel with the axis of the drum, such fluid being preferably divided into a plurality of streams. 115 These streams are preferably subdivided into a plurality of jets having an initial direction at an angle to radii of the drum. Within the drum the direction of movement of the fluid changes and the fluid 120 laden with fine particles flows from the drum at the same end at which it enters but at points within the points of entry.

In order to maintain a separation of the inflowing from the outflowing liquid, a dis- 130

tributing head A having inlet and discharge passages 15 and 25, is employed. The discharge passage has its inner end substantially central of the head so as to be in alignment with the outlet opening of the chamber 23. At its inner end the inlet passage is annular and connects with the annular chamber 16 from which the fluid passes into the drum.

- 10 In the form shown in Figs. 6 and 7 provision is made for the entrance of the air or fluid in a similar manner to that hereinbefore described and illustrated by Figures 1, 2, 3, 4, and 5, but provision is made for 15 the escape of fluid and fine material carried thereby through the perforated tube 30 in the manner described in application Serial No. 539,417 of February 27, 1922. Said tube is so supported that its axis will coincide 20 approximately with the axis of the drum. The outer end of the tube extends through the solid head 11^a as shown in Fig. 7 and is in alignment with the outlet passage 25 of the distributing chamber. The outer 25 end of the perforated tube 30 and the inner end of the outlet passage 25 are separated for the admission of additional fluid to the stream of fluid and pulverized material flowing from the tube 30 for the same purpose 30 that fluid is admitted through ports 24 in the form shown in Fig. 1. The flow of fluid through this opening is regulated by means of a movable collar or flange 31 sliding upon the outside of the wall of the 35 outlet passage 25 and adjusted by means of hand crank 32 acting upon pins 33 and 34.

The pulverizer shown in Figs. 6 and 7 is formed and constructed as hereinbefore described in Fig. 1, except that the head 11^c is made solid or imperforate. This head is protected on the interior against abrasion with liners as at 2^a, Fig. 1, and is provided with peripheral openings 12. Attached to the outer side of the head 11^c are 45 a series of radial vanes 42 spaced to form a number of channels 43 radiating from the center and corresponding in number to the peripheral openings 12. Covering these channels and coming into close contact with the outer edges of the vanes is an outer hood 44 which is attached to the rotating drum in the same manner as is the hood 17, Fig. 1. At the outer end of this hood 44 an opening is formed which registers with the 50 inner open end of the distributor head A. Fluid enters the distributor-head at 35, passes through channel 38 on one side of shutter 37, enters channels 43, passes through opening 12 in end head 11^c, through fluid channels 10, perforations 14, into the drum, passing through the drum interior where it becomes laden with fine material and leaving drum on opposite side through perforations 14, channels 10, ports 12, channels 55 43, and leaving distributor head through

the channel 39 on opposite side of the shutter 37 from that in which the air or fluid enters, thence out through the outlet port 36.

As shown in Fig. 8 the improved distributor can be so combined with the type 70 or construction of ball mill that the fluid will enter one end of the drum adjacent to its periphery and circulating through the drum and will flow therefrom carrying pulverized material through openings in the 75 head at the same end it entered, the discharge openings being arranged within the inlet ports.

As shown in Fig. 8 a rotating drum 1^a protected on its interior by hard metal 80 liners, and equipped at one end with any suitable feeding device, is provided at the end opposite the feeding mechanism with a screen or grating 11^a attached to casing 1^a. Attached to the periphery of the casing at 85 the discharge end is an outer hood 17^a which is provided on its inner side with a series of radial vanes 45 forming a series of pockets having their inner ends open for the reception of pulverized material which may drop 90 from the stream of fluid and pulverized material flowing from the drum. As the drum rotates, the material will drop from the pockets into the stream flowing from the drum.

Means such as are shown in Fig. 1 at 18, 19, and 20, are employed for forming a tight joint between the outer end of the cone 17^a which rotates with the drum and the inner end of the stationary distributor C.

An inner cone 21^a is attached to the distributor head C at the inner end of the outlet passage 25 in an adjustable manner, as indicated. This cone flares out peripherally leaving an annular opening around its entire 105 circumference between its inner edge and the face of the screen or grating 11^a.

In operation, the fluid employed enters at the lower passage 15^c of the distributor head, passes through the chamber 16^a formed by 110 the cones 17^a and 21^a, sweeping the pockets between the radial ribs 45 and enters the drum through the ports 12^b. Within the drum the fluid will move inwardly towards the axis of the drum picking up the pulverized material and escaping through the openings in the screen or grating 11^a and will flow through the cone 21^a and the discharge passage 25 in the distributor head. Whatever additional fluid is required for 115 the inward movement of the material for effecting classification or combustion, will be supplied from the chamber 16^a, such fluid passing from the chamber through the annular opening between the cone 21^a and the screen or grating.

It will be observed that the chambers or passages through which the fluid passes after picking up pulverized material, are surrounded by fluid of a higher pressure than 120

the portions carrying the pulverized material, and hence there will not be any escape of pulverized material through loose or defective joints but the fluid, free from pulverized material, will flow inwardly through such joints.

It will be understood that although it is preferred to force the fluid through the mill by a fan, blower, or pump, connected to the inlet passage of the distributing head, the carrying fluid may be drawn through the mill.

I claim herein as my invention:

1. The method herein described of removing pulverized material which consists in causing fluid to enter the drum in which pulverization is effected at points adjacent to the periphery of the drum and in a direction substantially parallel with the axis of the drum, and to flow from the drum in a reversed direction.

2. The method herein described for removing pulverized material which consists in causing fluid to flow into one end of the drum in which pulverization is effected at points adjacent to the periphery of the drum and in a direction substantially parallel with the axis of the drum, and to flow from the same end of the drum at points within the points of entry.

3. The method herein described of removing pulverized material which consists in causing fluid to flow into one end of the drum in which pulverization is effected in annularly arranged jets or streams and to flow from the same end of the drum, such outflow being along the annular space enclosed by the inflowing streams.

4. The method herein described of operating a pulverizing mill utilizing the flow of a fluid for removing fine particles from the mill, which consists in surrounding the portions of the fluid carrying the fine particles with fluid at a higher pressure than the dust laden portions.

5. A pulverizing mill having a drum having longitudinal passages adjacent to its periphery and an annular chamber communicating with such passages and provided with outlet openings arranged to discharge into the space within the annular chamber in combination with a head having passages communicating respectively with the annular chamber and with the space enclosed thereby.

6. A pulverizing mill having a drum provided with a series of longitudinal passages, adjacent to its periphery and having perforated walls in combination with spaced annular walls or hoods so supported at one end of the drum as to form an annular chamber communicating with the passages, a head for the drum having openings therethrough permitting of the flow of fluid into the chamber formed by the inner wall

or hood, a distributing head provided with passages communicating respectively with the annular chamber and with the chamber formed by the inner annular wall or hood.

7. A pulverizing mill having a drum provided with a series of longitudinal passages arranged adjacent to its periphery and having perforated walls in combination with spaced annular walls or hoods so supported at one end of the drum as to form an annular chamber communicating with the passages, a head for the drum having openings permitting of the flow of fluid into the chamber formed by the inner wall or hood, ports or openings for the flow of fluid from the annular chamber into the chamber formed by the inner wall or hood, a distributing head having inlet and outlet passages communicating respectively with the annular chamber and with the chamber formed by the inner annular wall or hood.

8. A pulverizing mill having a rotating drum provided with longitudinal passages arranged adjacent to its periphery and having perforated walls in combination with spaced annular walls or hoods so secured to the one end of the drum as to form between an annular chamber communicating with the passages, a head for the drum having openings permitting the flow of fluid from the drum into the chamber formed by the inner wall or hood, vanes carried by the inner hood for carrying pulverized material up to a point where it will drop into the fluid flowing into the inner annular wall or hood, a stationary distributing head having inlet and outlet passages communicating respectively with the annular chamber and with the chamber formed by the inner annular wall or hood.

9. A pulverizing mill having a rotating drum in combination with annular walls or hoods so supported at one end of the drum as to form with the head of the drum an annular inlet chamber and an inner discharge chamber communicating with the drum, a distributing head having inlet and outlet passages communicating respectively with the annular inlet chamber and the discharge outlet chamber formed by the inner annular wall or hood, and a classifier connected to the discharge passage in the head.

10. A pulverizing mill having a rotating drum in combination with annular walls or hoods so supported at one end of the drum as to form with the head of the drum an annular inlet chamber and an inner discharge chamber communicating with the drum, a distributing head having inlet and outlet passages communicating with the annular inlet chamber and the discharge or outlet chamber formed by the inner hood, a classifier connected to the discharge passage in the head and means for supplying additional fluid to the fluid flowing from the drum.

11. A pulverizing mill having a rotating drum in combination with annular walls or hoods so supported at one end of the drum as to form with the head of the drum an annular inlet chamber and an inner discharge chamber communicating with the drum, a distributing head having inlet and outlet passages communicating respectively with the annular inlet chamber and the discharge chamber, and a classifier connected to the discharge passage in the head. 40
12. A pulverizing mill having a rotating drum in combination with conical hoods so supported as to form with the head of the drum an annular inlet chamber and an outlet chamber, a classifier and stationary distributing head provided with passages communicating respectively with the annular inlet chamber, the outlet chamber and the classifier. 45
13. A drum for a pulverizing mill having in combination a casing and a plurality of annular transversely grooved liners fitting within the casing and adapted to form with the casing, passages, extending longitudinally of the drum, said liners having perforations for the flow of fluid into the drum. 50
14. A pulverizing mill having a drum provided with longitudinal passages adjacent to its periphery in combination with walls arranged at the end of the drum to form an annular chamber communicating with said passage and a central chamber communicating with the drum, a head having passages communicating respectively with the annular and central chambers. 55
15. A pulverizer in combination with a head interposed between the fluid supply and the mill and provided with a passage for the inflow of air, a passage for the flow of dust laden fluid from the mill, and a by-pass communicating with the supply and the outlet passage, and means for regulating the flow of fluid through the by-pass. 40
16. A rotatable pulverizing mill in combination with a stationary distributing head provided with a passage for conducting fluid to the mill and with a passage for conducting fluid discharged from the mill, and a passage for conducting clean fluid to the discharge passage. 50
17. A rotatable pulverizing mill in combination with a stationary head, provided with a passage for conducting fluid flowing from the mill and means for maintaining outside the joint between the head and mill a fluid under pressure higher than that flowing from the mill. 55
- In testimony whereof, I have hereunto set my hand.

RALPH E. H. POMEROY.
